ONE-THIRD TO PATRICK HENRY MURPHY, OF ENDERBY, BRITISH COLUMBIA,
CANADA.

CLOTHES-LINE SUPPORT.

1,130,534.

Specification of Letters Patent.

Patented Mar. 2, 1915.

Application filed July 5, 1913, Serial No. 777,596. Renewed July 23, 1914. Serial No. 852,760.

To all whom it may concern:

Be it known that I, JOHN T. PILKINGTON, a subject of the King of Great Britain, and a resident of Enderby, in the Province of 5 British Columbia and Dominion of Canada, have invented a new and Improved Clothes-Line Support, of which the following is a full, clear, and exact description.

My invention relates to means for supporting a pulley line, and particularly to 10 supporting means adapted to be affixed to the side of a house and to a post, or to two posts or other equivalent uprights.

An object of my invention is to provide 15 pulley supporting means so arranged that a free space is provided at all sides of the pulleys so that an endless clothes line, with clothes hung thereon, may freely pass, with the clothes, around both pulleys.

20 A further object of the invention is to provide pivoted pulley-supporting arms having guard pulleys to prevent the clothes line from leaving the main pulleys regardless of the angular positions of said arms, 25 and also to provide pivoted brace elements adjustable to engage the pulley arms in different positions of the latter.

The invention will be particularly explained in the specific description following.

30 Reference is to be had to the accompanying drawings forming a part of this specification, in which similar characters of reference indicate corresponding parts in all the views.

35 Figure 1 is a side elevation of the clothes line support embodying my invention; Fig. 2 is a partial plan view on a larger scale; and Fig. 3 is a partial end view of one of the supporting devices.

40 In carrying out my invention similar supporting means are provided for each end of the line and adapted respectively to be secured to posts, or to a house and posts, there being shown in the present example a post 45 10 and also a line 10^a which may indicate the side of a house. It will suffice to describe in detail one of the sets of supporting devices.

45 My improved device comprises a vertical 50 pin 11, adapted to turn in brackets 12 or other suitable supports, which may be secured in place by nails or screws 13. An arm 14 is secured to a clip 15 on the pin 11, so as to turn in a horizontal plane, or

approximately so, the said arm being connected with the clip by a horizontal pivot 16. The arm 14 carries at the under side thereof the horizontal pulley 17, around which the endless clothes line A runs. Said pulley may be mounted on the arm 14 in 60 any suitable manner, as by a keeper 18.

A brace arm 19 is employed in connection with the arm 14, and extends from a clip 15^a on the upper end of the vertical pin 11 downward diagonally to the outer end of 65 said arm 14. The brace 19 is pivotally connected with the clip 15^a, as at 19^a, to have movement in the vertical plane, and its lower end is adapted to engage a rack 20, the arrangement being such that the arm 70 14 can be given an inclination to suit the extent of sag in the line due to the weight of the clothes, and the brace 19 will hold the said arm 14 in the adjusted position. Thus there will be no tendency of the line 75 to leave the pulleys. When the line is empty, if it is a short light one, the weight of the pulleys and their arms will cause them to drop lower, and in this case the braces 19 will slip along the racks 20. At 80 the outer end of the arm 14 I may provide a transverse pin or shaft 21 carrying guard sheaves 22 disposed at a right angle to the plane of rotation of the pulley 17 for holding the line A against displacement. 85

It will be observed that the guard pulleys 22 are above and directly adjacent to the clothes line and its path of movement to and from the main pulleys 17, and that these guard pulleys are carried by the arms 14 90 nearer the free ends of the arms than the said main pulleys; also that the main pulleys are peripherally grooved. By this arrangement the provision of guard pulleys at the upper side only of the line serves to 95 prevent the line from slipping from the main pulleys, and furthermore the line is permitted a direct path to and from the main pulleys without any sidewise deflection. Moreover, as the arms 14 swing downwardly, due to the sagging of the line when clothes are hung thereon, the guard pulleys determine the point of bending of the line distant from the main pulleys whereby to 100 resist the tendency of the clothes line to 105 leave the main pulleys when the arms assume an angle to the general direction of the line.

Having thus described my invention, I claim as new, and desire to secure by Letters Patent:

1. A clothes line support, comprising an arm, a pulley thereon to receive a clothes line, said arm being mounted to turn on a horizontal pivot and subject to sag in the line to swing downwardly under the weight of clothes on said line, to dispose the pulley at a desired angle in response to the sagging of the line, and a brace arm pivoted to swing in a vertical plane and movably engaging with the pulley-supporting arm to accommodate itself to a downward movement of the latter.
2. In a clothes line support, a pulley-carrying arm, a pulley thereon, a rack on the upper side of the arm, the said arm being pivoted to assume a downward inclination, and an arm above the pulley-supporting arm, pivoted at one end to rock in a vertical plane, the free end of the second mentioned arm engaging the rack on the pulley-supporting arm.
3. In a clothes line support, a vertical pin, securing devices for the pin, clips on the pin at its upper and lower ends respectively, a pulley-supporting arm pivotally connected with the lower clip to rock in a vertical plane, a brace arm pivoted to the upper clip

to swing in a vertical plane, a pulley on the under side of the first arm, and a rack on the upper side of said arm, the brace arm extending diagonally downward and engaging by its free end with the said rack.

35

4. A clothes line and support comprising arms pivoted at one end to swing in a vertical plane, main pulleys on said arms near the free ends, an endless clothes line running around said pulleys, and guard pulleys carried by the pivoted arms to swing therewith, said guard pulleys turning on horizontal axes and said main pulleys turning in planes approximately at right angles to the planes in which the guard pulleys turn, said guard pulleys having their peripheries above and adjacent to the path of movement of the line and being positioned nearer the free ends of the arms than the first pulleys whereby to determine the point of bending of the line as the latter sags under the weight of clothes hung thereon.
